[57] **CLAIM**

The ornamental design for the tool handle, as shown and described.

DESCRIPTION

FIG. 1 is a front perspective view of the tool handle showing our new design;

FIG. 2 is a rear elevational view;

FIG. 3 is a top plan view; and,

FIG. 4 is a bottom plan view thereof.

The fragmentary tool shaft depicted by means of broken lines in FIG. 1 and 2 has been shown for illustrative purposes only and forms no part of the claimed design.
